UNITED STATES PATENT OFFICE.

ANTON PFISTER-SCHMIDHAUSER, OF ST. GALL, SWITZERLAND.

THERAPEUTIC BATH.

SPECIFICATION forming part of Letters Patent No. 712,436, dated October 28, 1902.

Application filed May 4, 1900. Serial No. 15,528. (No model.)

To all whom it may concern:

Be it known that I, ANTON PFISTER-SCHMIDHAUSER, a citizen of the Republic of Switzerland, residing at St. Gall, Switzerland, have 5 invented new and useful Improvements in Therapeutic Baths, (for which I have filed patents in Belgium, March 16, 1900, application No. 117,275; in Great Britain, March 20, 1900, numbered 5,295, and in Germany, 10 January 29, 1900, numbered 129,388 and 129,389,) of which the following is a specification.

This invention has relation to therapeutic baths; and it has for its object the provision 15 of means whereby certain portions of the body can be exposed more directly than others to the action of the therapeutic agent, such as hot air, vapor, or the like.

The accompanying drawings illustrate by 20 vertical sections a therapeutic bath embodying my invention.

Figure 1 shows the appliances for directing the flow of vapor in their relative positions to cause such vapor to flow through the seat only. Fig. 2 shows said appliances in their 25 respective positions to cause the vapors to flow both through the seat and into the lower part of the compartment for the lower limbs and thence into the upper part of the bath, 30 and Fig. 3 shows said appliances in their respective positions to cause the vapors to flow through the compartment for the lower limbs only and thence into the upper part of the bath.

35 The bath consists of a suitable box open at top and divided by a seat 25 and a foldable partition 29 30 into three compartments—namely, an upper compartment 24, a lower chamber 22, containing the vapor-generator 40 23 of a well-known construction, the means for supplying heat to the boiler being omitted in Fig. 1, and a front compartment 27 for the legs, the floor of which compartment constitutes the foot-rest. The seat 25 is an open 45 or slat seat supported from a suitable frame 26, secured to the box-walls, and to the front end of said seat is hinged the section 29 of the aforesaid sectional partition, section 30 of which is hinged to said section 29, so as to 50 fold thereon, as shown in Fig. 2, so that vapor from the generator 23 will flow about the lower part of the legs into compartment 27

and thence into the upper compartment 24, such vapor also flowing direct from the generator-chamber through the slats of the seat. 55

To prevent the section 30 from dropping when folded onto section 29, as shown in Fig. 2, I provide a hook-latch 32, pivoted to one of the side walls of the box, or such a hook-latch may be provided at either side of the seat 25. 60

By unlatching the section 30 and allowing it to drop, as shown in Fig. 1, the flow of vapor to the leg-compartment is cut off, the partition 29 30 fitting the opening in the vertical wall between the generator and leg compartments. 65

The foldable partition 29 30 is larger than the seat-supporting frame 26, so that by lifting the seat into a vertical position said partition 29 30 can be swung under it, as shown 70 in Fig. 3, thus forming a closure between compartments 24 and 22 and preventing vapor from rising through the seat, all the vapor from generator 23 flowing through the aperture in the vertical wall between compartments 22 and 27, as will be readily understood. 75

Of course it will be understood that in conjunction with the bath described a suitable covering provided with an aperture for the 80 passage of the head of the patient and not permeated or readily permeated by the therapeutic agent is used, as is the general practice, to prevent said agent from flowing or readily flowing from the upper compartment 85 of the bath.

Having thus described my invention, what I claim as new therein, and desire to secure by Letters Patent, is—

1. A therapeutic bath, comprising a chair-like structure provided with a projecting elevated foot-rest, said structure closed on all sides except at top and forming with the foot-rest intercommunicating compartments for the body and legs, an opening in the bottom 95 of the structure, a vapor-generator fitting said opening, an open-work seat above said generator and foot-rest and means for directing the vapors through the seat only, or through the leg-compartment or through both, 100 substantially as and for the purposes set forth.

2. The combination with the box or case, a seat-supporting frame and a movable slat-

seat dividing said box into upper and lower compartments, and a compartment 27 in communication with said lower compartment; of the foldable partition 29 30 hinged to the forward end of the seat and operating substantially as and for the purpose set forth.

5 In testimony whereof I have signed my

name to this specification in the presence of two subscribing witnesses.

ANTON PFISTER-SCHMIDHAUSER.
